DESIGN FOR A MITT

Mathilda Hacker, New York, N. Y.

Application January 12, 1942, Serial No. 105,159

Term of patent 3½ years

To all whom it may concern:

Be it known that I, Mathilda Hacker, a citizen of the United States, residing in New York city, in the county of The Bronx and State of New York, have invented a new, original, and ornamental Design for a Mitt, of which the following is a specification, reference being had to the accompanying drawing, forming part thereof.

Fig. 1 is a front view of a mitt showing my new design.

Fig. 2 is a rear view of Fig. 1 on a reduced scale.

Fig. 3 is a side view of the mitt shown in Figs. 1 and 2 on a reduced scale.

I claim:

The ornamental design for a mitt, substantially as shown.

MATHILDA HACKER.
